UNITED STATES PATENT OFFICE

EDNA R. GEDGE, OF LOS ANGELES, CALIFORNIA, ASSIGNEE TO PEERLESS PRODUCTS CO., A CORPORATION OF CALIFORNIA

CARTRIDGE-HOLDING FLOOR POLISHER

Application filed January 21, 1926. Serial No. 22,735.

It is an object of my present invention to provide improved means for introducing wax into and delivering wax from floor polishers of the general character described in my Patent No. 1,599,708, Sept. 14, 1926, and Patent No. 1,691,024, November 6, 1928, and, whereas the mentioned embodiments of my invention include means whereby the rotation of a handle, provided for the manipulation of the waxer body, is effective to express wax from a wax chamber (the wax being initially placed in this chamber by any preferred filling operation) it is an object of my present invention to provide means enabling the numerous users of my waxers to charge the same, in a cleanly, expeditious and economical manner, by the bodily insertion of novel wax cartridges in wax chambers especially adapted to receive the same; and my present invention may accordingly be regarded as comprising not only an improved waxer and polisher but also novel wax cartridges adapted to interfit therein and to cooperate with parts thereof, as hereinafter described.

Other objects of my invention, including the provision of special wax containers or chambers adapted to be disposed at the lower ends of handles and preferably each having a smooth interior and/or an interiorly threaded cap, said invention including also the use of a plunger having a smooth exterior, and means for so connecting the same with a handle that the rotation of said handle advances said plunger, may be best appreciated from the following descriptions of alternative embodiments of my present invention, taken in connection with the appended claims and the accompanying drawings, in which

Fig. 1 may be regarded as, for the most part, a substantially central vertical section through a wax organization illustrating one form of my present invention,—this view being taken substantially in the plane of the line 1—1 of Fig. 2 (which, however, shows an alternative form of wax cartridge).

Fig. 2 is a detail view, taken substantially as indicated by the line 2—2 of Fig. 1, but showing, as indicated, an alternative form of wax cartridge.

Fig. 3 is a view corresponding to a portion of Fig. 2, but suggesting the use of a wax cartridge in the form of a collapsible tube.

Fig. 4 is an elevational view comparable with the upper portion of Fig. 1, but showing an alternative embodiment of my invention in which, both during ordinary manipulation (for a waxing or polishing effect) and during the expressing of wax (by the rotation of a handle) a threaded cap, provided above a wax chamber may remain stationary, relatively to said chamber.

Fig. 5 is a view comparable with Fig. 4 but showing an alternative form of plunger,—designed for use in the stripping of wax from wax cartridges in the form of collapsible tubes.

Fig. 6 is a perspective view showing the upper or closed end of one advantageous form of a collapsible tube wax cartridge,—comprising parts so designed or disposed as to facilitate a holding of same during a stripping of wax therefrom, as by means of a plunger of the general type illustrated in Fig. 5.

Fig. 7 is a longitudinal or a vertical sectional view through one advantageous type of cartridge comprising a thin but substantially rigid shell.

Figs. 8 and 9 are respectively longitudinal or vertical sections, and

Fig. 10 is an elevational view, of further alternative forms hereinafter described.

Referring to the details of that specific embodiment of my invention shown in Fig. 1, 11b being the main body of a waxer or polisher of the general type illustrated in my mentioned pending applications, 12b is a cylindrical wax container pivoted thereto and disposed coaxially with a main operating handle 13b,—suitable for use in the application of wax and/or the polishing of floors, or the like, by means comprising the main head or body 11b, duly protected.

In this form of my invention, instead of providing threads directly upon a handle 13b or upon a thimble or plunger 14b, integrally or rigidly connected therewith, in order to adapt the said thimble or plunger to fit and advance within a wax cartridge comprising a

cylindrical shell 15b, I avoid providing any threads directly upon the thimble or plunger 14b, preferably providing external threads at 16b, near the upper end of the wax container 12b, and providing internal threads, as at 17b upon a cap member 17b', integrally or otherwise rigidly connected with the plunger or thimble 14b,—as by means of a screw or pin extending therethrough.

10 In order that an advance of the plunger or thimble 14b, as occasioned by a relative rotation between the wax container 12b and the cap 17b' shall be effective to cause an advance or expression of wax from within a wax cartridge, of the general character referred to, 15 and through, for example, a conical head 18b, shown as integral with an offset neck 19b, at the lower end of the wax container 12b (said conical head being preferably integral with a threaded extension such as is shown at 20b, 20 Fig. 2, adapted to carry a nut, or the like, and suitable washers for the retention of said conical head within a corresponding conical seat provided in an upstanding lug or projection 21b, as described in my last mentioned 25 prior application, the offset neck 19b and the projection 21b being respectively provided with means such as cooperating ducts 23b and 24b for the conduction of wax toward the 30 lower surface of the main body 11b', it is important that the thimble or plunger 14b, or its equivalent, shall fit somewhat exactly, whether or not it is rotated within the cartridge shell 15b, or its equivalent; but said 35 shell may fit somewhat loosely and be freely movable within the wax container 12b; and, in order to facilitate the insertion, retention and replacement of a wax cartridge of the general character shown in Figs. 1 and/or 7, 40 and in order reliably to guide the thimble or plunger 14b, or its equivalent thereto, the upper or entrance end of the cartridge shell 15b, may advantageously be outwardly flared, somewhat as suggested at 25b, so as to overlie 45 a terminal shoulder 26b at the upper end of the container 12b.

In order to assure a substantially circular cross sectional outline and a uniform thickness of wall, I suggest the formation of the 50 mentioned cartridges from extruded, or drawn or other tubular stock, rather than from a sheet material; and, although the respective ends thereof may be closed in any preferred manner, I suggest in Fig. 7, the use 55 of a cap 27b at the lower end of a cartridge 28b and the use of a cupped or other plug 29b at the opposite or upper end thereof. The diameter of the cap 27b, when employed, may be such as to prevent the insertion of the 60 cartridge within the chamber 12b, or its equivalent, until the said cap is removed; and the cupped plug 29b, or its equivalent, may be adapted to form a wedging fit with the 65 mentioned flared terminal portion 26b, at the 85 upper end of the shell 15b,—one or both of the

mentioned closure elements incidentally providing circumferential channels 30b, suitable for the retention of any preferred sealing compound or material.

In Fig. 2 I suggest the use of an alternative 70 type of cartridge 28c, the upper end thereof being, for example, similar to that of the described cartridge 28b, but the lower end thereof being shown as closed by a transverse element 31c, permanently secured to a thin shell 15c and provided with an eccentrically disposed threaded nipple 32c,—a correspondingly threaded cap (not shown) having been removed before the mentioned nipple is inserted 75 in the manner illustrated.

80 Although a user might obviously use a cartridge in the form of an ordinary collapsible tube, permitting the wax delivered therefrom upon compression by a plunger 14b, 14c, or its equivalent, to exit either 85 through a lateral opening into an offset neck, as shown at 23b, Fig. 2, or through a centrally positioned opening, as suggested at 23d, Fig. 5, it will be obvious that the removal 90 of the shell of a longitudinally crushed cartridge from a deep wax chamber may present a disagreeable problem; and I accordingly illustrate in Figs. 4 and 5 alternative constructions which, although they may be employed in connection with cartridges of the 95 general character already described, are particularly suitable to use in connection with the expression of wax from so-called collapsible tubes. In Fig. 4 I show a cylindrical wax container 12e as provided with a 100 cap 17e which, although internally threaded at 16e for engagement by a correspondingly threaded member which may be integrally or otherwise rigidly connected with a main handle for the manipulation of a polisher, is provided with quick-detachable means, involving no use of a thread, for its connection to and disconnection from said wax container,—the mentioned cap and container being respectively provided with cooperating 105 shoulders 26e and 33e, adapted to cooperate 110 in the retention of a flared portion 25e of a wax cartridge shell.

115 For the purpose referred to, I may provide the container 12e with a plurality of projecting lugs 34e, interfitting within circumferential portions 35e of slots 36e, in the manner of so-called bayonet connections; and, in order that the rotation of the handle or other threaded member 13e, shown as carrying at 120 its lower end a plunger 14e, for the purpose of expressing the contained wax from the shell 15e, shall be ineffective to disconnect the cap 17e from the container 12e, I may provide, in connection with the described bayonet joint, or its equivalent, any desired latching or restraining means, such as, for example, a resilient dog 37e. Although this form of my invention is suitable for use with cartridges comprising rigid shells, it is also suit- 125 130

able for use with cartridges in the form of removable tubes,—the closed ends thereof being merely cut off, as with a knife or shears, and the metallic walls being so flared as to be engageable in the indicated manner between the described container and cap.

In Fig. 5 I show a form of my invention, comparable with that just described, but providing means for the use of a collapsible tube without cutting the same in such manner as to permit a plunger to pass therethrough. In this form of my invention, optionally using a chamber 12f of the general character illustrated in Fig. 4 and similarly connected with a removable cap 17f; I show a plunger 14f as substantially spherical in outline and as secured to the lower end of an operating handle 13f by a swivelled and play-permitting connection comprising a screw 38f, shown as contained in the ball plunger 14f (optionally by the aid of a lock nut 39f) and as rotatable within a socket 40f, at the lower end of the mentioned handle 13f,—said socket being formed in part by a removable section 41f, shown as secured by a screw 42f. In the use of this form of my invention the upper end of a collapsible tube cartridge 12f may be retained between shoulders 26f and 33f in such manner that, upon the descent of the plunger 14f, or its equivalent, the contained wax is stripped from said tube, the upper end of said tube remaining conveniently accessible, for removal, upon the disconnection of the cap 17f from the container 12f.

Although collapsible tubes upwardly terminating in an ordinary manner may, especially if not initially filled quite full of wax, be secured and used in the general manner described, I prefer, after filling collapsible tubes with a suitable wax, to close the same in the general manner illustrated in Fig. 6,—the closing folds being given an arcuate form, as at 43f, in order to facilitate the insertion, retention and removal of the same in the general manner described.

In Fig. 8 I show an alternative in which a cap member 17g is secured to a wax container 12g by a hinge 44g, a spring clip 45g being secured, as by rivets 46g, to one of these members and adapted releasably to engage a projection 47g on the other; the plunger 14g and shoulders 26g and 33g being adapted to function and cooperate in the general manner above described.

In the form shown in Fig. 9, instead of using (as in the embodiments illustrated in Figs. 4 and 5) a comparatively shallow cap element associated with a deep container to receive the lower end of a wax cartridge, I associate a comparatively shallow container 12h with a comparatively deep cap 17h, interiorly threaded to receive a correspondingly threaded handle 14h; and, instead of connecting the mentioned container and cap by

a bayonet joint or by a hinge or other means of the general character above described, I may connect the same by means of an additional threaded connection such as is shown at 48h.

In Fig. 10 I illustrate an additional form,—in which a wax or cartridge container integral with a cap is split longitudinally into halves 12i and 12i', connected by a hinge 44i and provided with a latch—shown as comprising a clip 45i adapted to engage a cooperating projection 47i.

Using this form of my invention, the threads on the respective halves being adapted to cooperate in receiving the threaded handle, terminating in a plunger head, incidentally to a recharging, the operative is enabled to restore the plunger to its upper position without rotating the same.

Although I have herein described several alternative embodiments both of my cartridge retaining means and cartridges for use therewith, I believe I am the first to provide a waxer with any means whatever permitting the use of insertable wax cartridges; I accordingly emphasize not only the fact that various features of my invention might be independently employed but also the fact that numerous modifications of my invention additional to those above described, might easily be devised by those skilled in the art to which this case relates, without involving the slightest departure from the spirit and scope of my invention, as the same is indicated above and in the following claims.

I claim as my invention:

1. In means of the general character described; a waxer body having a wax delivery passage; a handle for manipulation of said body; a wax container mounted on the lower end of said handle and provided with an interiorly threaded cap adapted to cooperate therewith; an apertured ear integrally formed on the top of the body and having a wax passage extending between the aperture in the ear and the wax delivery passage; said ear and container being pivotally joined; the container having an extension fitting into the aperture in the ear and arranged with a passageway communicating with the passageway in the ear; a plunger movable in the container; and means whereby axial movement of the handle is effective to move said plunger.

2. In means of the general character described; a waxer body having a wax delivery passage; a handle for manipulation of said body; a wax container mounted on the lower end of said handle; a plunger movable in the container; said container being provided with an interiorly threaded cap adapted to cooperate therewith for giving lateral movement to said plunger, and through which said handle extends; an apertured ear integrally formed on the top of the body and having a wax passage extending between the aperture

in the ear and the wax delivery passage; said ear and container being pivotally joined; the container having an extension fitting into the aperture in the ear and arranged with a passageway communicating with the passageway in the ear; and means whereby axial movement of the handle is effective to move said plunger.

3. In means of the general character described; a waxer body having a wax delivery passage; a handle for manipulation of said body; a wax container mounted on the lower end of said handle; said container comprises a part carrying a hinge; and a member so connected therewith as to provide access to the interior of said container; an apertured ear integrally formed on the top of the body and having a wax passage extending between the aperture in the ear and the wax delivery passage; said ear and container being pivotally joined; the container having an extension fitting into the aperture in the ear and arranged with a passageway communicating with the passageway in the ear; a plunger movable in the container; and means whereby axial movement of the handle is effective to move said plunger.

In testimony whereof, I have hereunto set my hand at Los Angeles, California, this 14th day of January, 1926.

EDNA R. GEDGE.
